(57) **CLAIM**

The ornamental design for a medical patch, as shown and described.

DESCRIPTION

FIG. 1 is a front view of a medical patch of the present invention.

FIG. 2 is a rear view thereof.

FIG. 3 is a top plan view thereof.

FIG. 4 is a bottom plan view thereof.

FIG. 5 is a right side view thereof.

FIG. 6 is a left side view thereof.

FIG. 7 is a perspective view thereof.

FIG. 8 is an enlarged view of the 8-8, 8-8 portion of FIG. 1.

FIG. 9 is an enlarged view of the 9-9, 9-9 portion of FIG. 2.

FIG. 10 is an enlarged view of the 10-10, 10-10 portion of FIG. 5.

FIG. 11 is a 11-11 sectional view of FIG. 8.

FIG. 12 is a 12-12 sectional view of FIG. 9.

FIG. 13 is a reference enlarged view of the 13-13, 13-13 portion with shading of FIG. 7.

FIG. 14 is a reference exploded view of the medical patch.

FIG. 15 is a reference view 1 of the medical patch showing the occasion of use.

FIG. 16 is a reference view 2 of the medical patch showing the occasion of use.

FIG. 17 is a front view of another medical patch of the present invention.

FIG. 18 is a rear view of the medical patch shown in FIG. 17.

FIG. 19 is a top plan view of the medical patch shown in FIG. 17.

FIG. 20 is a bottom plan view of the medical patch shown in FIG. 17.

FIG. 21 is a right side view of the medical patch shown in FIG. 17.

FIG. 22 is a left side view of the medical patch shown in FIG. 17.

FIG. 23 is a perspective view of the medical patch shown in FIG. 17.

(Continued)

FIG. 24 is an enlarged view of the 24-24, 24-24 portion of FIG. 17.

FIG. 25 is an enlarged view of the 25-25, 25-25 portion of FIG. 18.

FIG. 26 is an enlarged view of the 26-26, 26-26 portion of FIG. 21.

FIG. 27 is a 27-27 sectional view of FIG. 24.

FIG. 28 is a 28-28 sectional view of FIG. 25.

FIG. 29 is a reference enlarged view of the 29-29, 29-29 portion with shading of FIG. 23.

FIG. 30 is a reference exploded view of the medical patch of FIG. 17.

FIG. 31 is a reference view 1 of the medical patch of FIG. 17 showing the occasion of use; and,

FIG. 32 is a reference view 2 of the medical patch of FIG. 17 showing the occasion of use.

The features shown in broken lines depict environmental subject matter only and form no part of the claimed design.

1 Claim, 32 Drawing Sheets
